UNITED STATES PATENT OFFICE

168,109

FLEXIBLE BOTTLE

Jules B. Montenier, Chicago, Ill.

Application April 25, 1950, Serial No. 9,465

Term of patent 14 years

(Cl. D58—8)

To all whom it may concern:

Be it known that I, Jules B. Montenier, a citizen of the United States, residing at Chicago, in the county of Cook and State of Illinois, have invented a new, original, and ornamental Design for Flexible Bottle, of which the following is a specification, reference being had to the accompanying drawing, forming a part thereof.

In the drawing—

Fig. 1 is a front elevational view of a flexible bottle, showing my new design;

Fig. 2 is a side elevational view thereof; and
Fig. 3 is a top plan view thereof.

The dominant features of the design reside in the portions shown in full lines.

I claim:

The ornamental design for a flexible bottle, as shown and described.

JULES B. MONTENIER
